UNITED STATES PATENT OFFICE.

ARTHUR W. HOAG, OF NEW YORK, N. Y.

COMBINATION-LOCK.

No. 856,700.

Specification of Letters Patent.

Patented June 11, 1907.

Application filed August 14, 1906. Serial No. 330,530.

To all whom it may concern:

Be it known that I, ARTHUR W. HOAG, a citizen of the United States, residing at the city of New York, in the county of New York and 5 State of New York, have invented certain new and useful Improvements in Combination-Locks, of which the following is a specification.

My invention relates to combination locks which are designed primarily for use in pad 10 lock frames and my objects are to produce such locks cheaply, to provide mechanism for a large number of possible combinations in which the combination necessary to open the lock can be easily changed, and in which 15 the parts are easily accessible for repairs or changes and which cannot be easily picked or broken open.

I attain my objects in the manner illustrated in the accompanying drawing in 20 which

Figure 1 is a view of the complete pad lock with the shackle open; Fig. 2 a view partly in section of the structure of Fig. 1; Fig. 3 a like view on the line *a a* of Fig. 4; Fig. 4 a like view on the line *b b* of Fig. 2; Fig. 5 a 25 sectional detail view of the combination members on the line *b b* of Fig. 2; Fig. 6 a detail view of the combination members and bolt releasing dog; Fig. 7 a view of the 30 mechanism for locking the combination mechanism to the frame taken on the line *c c* of Fig. 2; and Fig. 8 a detail view of the shackle turning device.

The combination mechanism proper comprises an index plate 1, a dial plate 2, having 35 a knob 3 and a spindle 4 secured thereto. The index plate has a pair of posts 5 5 extending therefrom and a bridge piece 6 connecting them which acts as a bearing for the 40 inner end of the spindle. The index plate is also provided on its inner face with a plurality of hooks 7, 7, 7, which engage the frame and hold the combination mechanism therein.

A wheel 8 provided with peripheral sockets 45 9, 9, 9 is secured to the spindle inside of the index plate. Disks 10, 11 and 12, provided with peripheral notches 13, 14 and 15, are loosely mounted on the spindle 4 and are 50 separated from each other by collars 16. The inner end of the spindle carries an indicator 17 by means of which the combination can be learned and a spring 18 to give the necessary pressure to maintain the parts in frictional engagement. The first disk 10 is 55 provided with a finger 19 adapted to engage any of the sockets 9 in the disk 8 for the pur-

pose of locking the disk 10 and the figures on the dial plate 2 in any desired relation. The disks 10, 11 and 12 are provided with laterally projecting pins adapted to engage each 60 other on the revolution of the spindle. These pins are detachably secured to the disks so their relation to the notches may be varied at will.

To learn the combination the combination 65 mechanism must be removed from the frame and the disks turned alternately to the right and left until the notches are aligned with the indicator, the number on the dial opposite the index plate mark being noted as each notch 70 comes into position.

The pad lock proper comprises the frame 21 provided with the substantially circular opening in its face adapted to receive the combination mechanism. A sleeve 22 is inserted through a hole in the top of said frame and is provided with an internal, sliding, locking sleeve 23 which may be moved up or down by the screw 24. The outer sleeve is provided with an opening 25 adapted to receive a hook 7, and upon forcing the sleeve 23 downward its lower edge engages the hook and locks the combination mechanism to the frame, the other hooks engaging recesses in the opening in the frame. The upper end of 85 the sleeve carries a boss 26 adapted to engage the free end of the swinging, sliding shackle 27 and is provided with an opening through which the screw operating the locking sleeve is accessible. A second sleeve 28 90 is fastened in the frame on the other side and is provided with bolt slots 29, 29 on one side and a large opening 30 on the other. This large opening has an upwardly extending slot 30' at the top as shown in Fig. 8. 95

The shackle 27 has an extension 31 adapted to revolve in the sleeve 28 and terminates in a button head 32 which in turn engages the bolt plate 33. The shackle 27 and sleeve 28 are connected by a helical spring 34, one 100 end of which engages a hole in the shackle extension, and the other end of which is bent into a hook and engages the slot 30', the end being turned into the groove in the bolt plate when assembling as shown in Fig. 3 105 and then bent out to engage the slot as shown in Fig. 8. The bottom of the bolt plate 33 is connected to the sleeve 28 by a spring 35 which engages a cross bar 36, the tendency of the spring being to pull the 110 shackle 27 into the frame.

The bolt plate is provided with bolt holes

37 which align with the slots in the sleeve 28. A dog 38, provided with bolts 39, 39 is held away from the bolt plate by the action of the springs shown in Fig. 2. The peripheries of 5 the combination disks hold the dog 38 and bolts 39 in locked engagement with the slots 29 in the sleeve 28 except at such times as the notches are all aligned opposite the dog when the springs drive the bolts forward and 10 out of engagement with the slots.

The head of the sleeve 28 has a pin 42 which engages a recess 43 in the shackle when the lock is closed.

In use the disks are turned by means of 15 the knob and spindle alternately to the right and left until the notches have aligned opposite the dog when it moves into them by the action of the small springs around the bolts, the bolts being thereby disengaged from the 20 sleeve. On further turning of the spindle the squared side of the notch 13 engages the dog 38 and lifts the shackle until the free end clears the socket on the other side of the lock when the spring 34 gives the shackle a 25 rotary movement and opens the lock.

To close the lock the shackle is swung about until the free end can be pushed down into the socket and the spindle is revolved in a direction opposite to that used in raising 30 the dog. This causes the inclined side of the notch 13 to drive the dog and bolts into the bolt plate and lock the shackle.

The combination may be varied at will by 35 altering the position of one or more of the pins on the disks or by moving the disk 10 so that the relative position of its notch and the figures on the dial is changed or both methods may be combined.

One method of securing the sleeve 28 to 40 the frame is illustrated and comprises the lug 40 on the outside of the sleeve between which and the inner face of the frame a key 41 is driven. By this construction the combination mechanism must be removed before the key is accessible.

I claim:

1. A combination lock comprising an index plate, a dial plate; a spindle projecting therefrom; a wheel provided with peripheral sockets secured to said spindle; a plurality of notched disks loosely mounted on said spindle, one of which is secured to any desired socket on the wheel, laterally projecting pins secured to each of said notched 55 disks at a predetermined point; a locking bolt 39; and means controlled by said notched disks for throwing the bolt.

2. A combination lock comprising an index plate, a dial plate; a spindle projecting 60 therefrom; posts extending from the index plate; a bridge connecting said posts and forming a bearing for one end of said spindle; an indicator 17 on said spindle; a wheel provided with peripheral sockets secured to said 65 spindle; a plurality of notched disks loosely

mounted on said spindle one of which is secured to any desired socket on the wheel; a laterally projecting pin secured to each of said notched disks at a predetermined point; a spring between the bridge and disks to 70 maintain the parts in frictional engagement; a locking bolt; and means controlled by said notched disks for throwing the bolt.

3. A combination pad lock comprising a frame provided with an opening in one face 75 adapted to receive the combination mechanism; a shackle movably mounted in the frame; a plate; combination mechanism mounted on said plate; hooks projecting from said plate; a movable sleeve secured in 80 the frame and adapted to engage one of said hooks; and means for moving said sleeve into or out of engagement with said hook whereby the combination mechanism is secured to or released from the frame.

4. A combination pad lock comprising a frame; a sleeve in said frame provided with locking or bolt sockets 29; a shackle movably mounted in the frame; a spindle mounted in the frame; a plurality of notched disks 90 on said spindle; a bolt plate carried by the end of the shackle within the frame; a dog and bolts carried by said plate, the bolts being adapted to enter the sockets; means for aligning the notches in said disks to receive 95 the dog whereby the bolts will be withdrawn from the bolt holes permitting the lock to be opened.

5. A combination pad lock comprising a frame; a spindle in said frame; a plurality of 100 notched disks on said spindle; a slotted sleeve secured to the frame; a shackle movably secured in said frame; a bolt plate loosely secured to the end of said shackle within the frame; a dog and bolts carried by 105 said plate, the bolts being adapted to enter slots in the sleeve; means for aligning the notches on the disks opposite the dog for the purpose of withdrawing the bolts from the slots and moving the shackle to open the 110 lock.

6. A combination pad lock comprising a frame; a spindle in said frame; a plurality of 115 notched disks loosely mounted on said spindle; a slotted sleeve secured in said frame; a shackle movably mounted in said sleeve; a spring connecting said shackle and sleeve whereby the shackle is revolved on lifting it; a bolt plate loosely secured to said shackle within the sleeve; a dog and bolts carried on 120 said bolt plate the bolts being adapted to enter slots in the sleeve; means for aligning the notches on the disks opposite the dog for the purpose of withdrawing the bolts from the slots and moving the shackle.

7. A combination pad lock comprising a frame; a spindle in said frame; a plurality of 125 notched disks loosely mounted on said spindle; a slotted sleeve secured in said frame; a shackle movably mounted in said sleeve; a

bolt plate loosely secured to the end of the shackle within the frame; a spring secured to the bolt plate and the sleeve to exert a downward pressure on the shackle; a dog and bolts carried by said plate the bolts being adapted to enter the slots in the sleeve; means for alining the notches on the disks opposite the dog for the purpose of withdrawing the bolts from the slots and moving the shackle.

8. A combination pad lock comprising a frame, a spindle in said frame; a plurality of notched disks loosely mounted on said spindle; a slotted sleeve secured in the frame; a shackle movably mounted in the sleeve; a spring connecting the shackle and sleeve whereby the former is revolved on lifting it; a bolt plate loosely secured to the end of the shackle within the sleeve; a spring secured to the bolt plate and sleeve to exert a downward pressure on the shackle; a dog and bolts carried by said plate; the bolts being adapted to enter the slots in the sleeve; means for alining the notches in the disks opposite the dog for the purpose of withdrawing the bolts from the slots and moving the shackle.

9. A combination pad lock comprising a frame; combination mechanism consisting of an index plate; hooks on said plate; a dial plate; a spindle projecting therefrom a

wheel provided with peripheral sockets secured to the spindle; a plurality of notched disks loosely mounted on said spindle; one of which is secured to any desired socket in the wheel; a laterally projecting pin on each of said disks at a predetermined point; a movable sleeve secured to the frame and adapted to engage a hook on the index plate; means for moving said sleeve into or out of operative engagement with the hook; a second slotted sleeve fixed to said frame; a shackle movably mounted in said sleeve; a spring connecting said shackle and sleeve whereby a rotary movement is given the former on lifting it; a bolt plate loosely secured to the end of the shackle within the sleeve; a second spring connecting the bolt plate and sleeve whereby a downward pressure is exerted on the shackle; a dog and bolts on said plate the bolts being adapted to enter the slots in the sleeve; means for alining the notches in the disks opposite the dog for the purpose of withdrawing the bolts from the slots and moving the shackle.

In testimony whereof I have affixed my signature in presence of two witnesses.

ARTHUR W. HOAG.
